UNITED STATES PATENT OFFICE

ARTHUR RITSCHER, OF DRESDEN, GERMANY, ASSIGNOR TO UNITED CIGARETTE MACHINE COMPANY A.-G., OF DRESDEN-A., GERMANY

CIGARETTE PACKING MACHINE

Application filed January 5, 1931, Serial No. 506,812, and in Germany January 23, 1930.

This invention relates to cigarette packing machines and comprises an apparatus for rejecting incorrectly filled cigarettes or the like.

5 It is already known, in cigarette packing machines, to provide an electro-magnetic device for rejecting incorrectly filled packets, the said device chiefly comprising feeler levers which co-operate with the cigarettes placed in the packet and which, on one or more cigarettes being deficient set in operation an ejecting apparatus which moves the completely filled packet away from the operations on the correctly filled packets. It has already been previously proposed to adjust the mechanism so finely that it operates also when cigarettes which are too loosely filled are present in the packet and rejects the packet in question. These known devices, however, 20 have the disadvantage that when cigarettes which are too loosely filled are present, not only are the latter rejected, but the correctly filled cigarettes present in the same packet are rejected also.

25 According to the present invention, in order to obviate this disadvantage, the rejection of the incorrectly filled cigarettes is effected so as to move the cigarettes in question away from the operations on the correctly filled cigarettes during their forward movement to the packing machine. In order to cause the ejecting apparatus to operate when cigarettes containing too little or too much tobacco pass by the feeler levers acting upon the ejecting apparatus, the arrangement is preferably so contrived that the feelers, which are mounted rotatably and are provided with contacts which come into contact with stationary contacts during movement 30 in one or both directions, thereby closing in known manner the circuit of an electrical relay which controls the ejecting apparatus.

In order to include the entire length of the cigarettes, a plurality of feeler levers acting independently of one another are mounted side by side lengthwise of the cigarettes.

A constructional form of the invention is shown by way of example in the accompanying drawing, in which,

Figure 1 is a side elevation of a feed apparatus for cigarettes and

Figure 2 is a corresponding view in another working position of the apparatus.

Figure 3 is a vertical section through Figure 1.

The cigarettes *a* which are to be sent to the packing machine are fed in a known manner from a supply container *b* to a revolving drum *e* provided with peripheral grooves *d*, and are arranged in the grooves of the drum by a revolving roller *f*. According to the invention, a plurality of feeler levers *g* are pivotally mounted on a common shaft *h* on the upper side of the grooved drum *e*. Leaf springs *i* bear against the free ends of the feeler levers *g*, the lower part of which is arcuate, so that the feeler levers bear with a certain pressure against the periphery of the cigarettes *a* which are moved past beneath them by the grooved drum *e*. On the part of the feeler levers *g* which lies above the axle *h* are mounted two contacts *n*, *o* adjustable by screws *k* and *m*, respectively, and opposed on both sides by a stationary contact *p*, *q* respectively. The stationary contacts *p*, *q* are likewise adjustable by screws *r*, *s* and are connected together and to one end of the magnet winding of an electromagnet *t* by an electric lead *s*. The lead *s* is connected to a source of electric current *u*. The other end of the magnet winding *t* is connected by a lead *v* to the feeler levers *g* and to the contact pin *n*, *o* allocated to the said feeler levers. The electromagnet *t* co-operates with an armature lever *w*, which controls in any known manner a mechanical ejecting apparatus not shown in the drawing.

The mode of operation of the apparatus is consequently as follows:

If the cigarettes fed from the supply container *a* by the grooved drum *e* are filled with the correct amount of tobacco, the feeler levers *g* exploring the cigarettes are held in a position in which the contact pins *n* and *o* are out of contact with the contacts *p* and *q*, so that the circuit of the electromagnet *t* is interrupted. If, however, a cigarette which is filled for example with too little tobacco comes under the feeler levers *g*, then owing

to the smaller resistance, one or more feeler levers *g* will be moved into the position shown in Figure 2, in which the contacts *p* and *n* touch one another, thus closing the circuit of the electromagnet *t*. The result of this is that the armature lever *w* is attracted by the electromagnet *t* and the ejecting apparatus is set into operation, so that on further forward movement, the cigarette in question is rejected from the course of the correctly filled cigarettes. Conversely, for the case in which the cigarette contacting with the feeler levers *g* contains too much tobacco, a movement of one or more feeler levers *g* takes place in the other direction, so that the contacts *o* and *q* touch one another and the circuit of the electromagnet *t* is again closed.

The invention is of course not limited to the constructional form illustrated and may be used with feed devices of any construction. The feeler levers or the like, which explore the cigarettes may if desired co-operate with a mechanical relay instead of with an electrical relay, or may serve directly for controlling the ejecting apparatus. In order that the ejecting apparatus will come into operation when the badly filled cigarette contains too much or too little tobacco on a portion of its length only, a large number of feeler or exploring levers will preferably be distributed over the entire length of the cigarette, although in certain cases, the provision of only one feeler lever may be sufficient.

I claim:—

- 35 1. An apparatus for detecting and setting an ejecting apparatus in operation for an incorrectly filled cigarette or the like, comprising an individual feeding device for the cigarettes; a feeler along which the cigarettes are individually fed by said feeding device thereby contacting the cigarettes individually; and means cooperating with the feeler to set the ejecting apparatus in operation when a cigarette detected by the feeler contains an under or over supply of tobacco.
- 40 2. An apparatus for detecting and setting an ejecting apparatus in operation for an incorrectly filled cigarette or the like, comprising an individual feeding device for the cigarettes; a feeler along which the cigarettes are individually fed by said feeding device thereby contacting the cigarettes individually; and means including a plurality of electrical contacts cooperating with the
- 45 3. An apparatus for detecting and setting an ejecting apparatus in operation for an incorrectly filled cigarette or the like, comprising an individual feeding device for the cigarettes; a feeler along which the cigarettes are individually fed by said feeding device thereby contacting the cigarettes individually; and means including a pair of electrical contacts
- 50 4. An apparatus for detecting and setting an ejecting apparatus in operation for an incorrectly filled cigarette or the like, comprising an individual feeding device for the cigarettes; a feeler along which the cigarettes are individually fed by said feeding device thereby contacting the cigarettes individually; and means including a pair of electrical contacts
- 55 5. An apparatus for detecting and setting an ejecting apparatus in operation for an incorrectly filled cigarette or the like, comprising an individual feeding device for the cigarettes; a plurality of feelers pivotally arranged side by side lengthwise and along which the cigarettes are individually fed by said feeding device thereby contacting the cigarettes individually; and means cooperating with the feelers to set the ejecting apparatus in operation when a cigarette detected by one or more of the feelers contains an under or over supply of tobacco.
- 60 6. An apparatus for detecting and setting an ejecting apparatus in operation for an incorrectly filled cigarette or the like, comprising an individual feeding device for the cigarettes; a plurality of spring-pressed feelers pivotally arranged side by side lengthwise and along which the cigarettes are individually fed by said feeding device thereby contacting the cigarettes individually; and means cooperating with the feelers to set the ejecting apparatus in operation when a cigarette detected by one or more of the feelers contains an under or over supply of tobacco.

dividually; and means including a pair of stationary electrical contacts and a pair of electrical contacts on the feeler to electrically set the ejecting apparatus in operation by one contact on the feeler contacting with its stationary contact when a cigarette detected by the feeler contains an under or over supply of tobacco.

70 4. An apparatus for detecting and setting an ejecting apparatus in operation for an incorrectly filled cigarette or the like, comprising an individual feeding device for the cigarettes; a feeler along which the cigarettes are individually fed by said feeding device thereby contacting the cigarettes individually; and means including a pair of stationary electrical contacts and a pair of electrical contacts on the feeler to electrically set the ejecting apparatus in operation by one contact on the feeler contacting with its stationary contact when a cigarette detected by the feeler contains an under or over supply of tobacco, said contacts being adjustably mounted.

75 5. An apparatus for detecting and setting an ejecting apparatus in operation for an incorrectly filled cigarette or the like, comprising an individual feeding device for the cigarettes; a plurality of feelers pivotally arranged side by side lengthwise and along which the cigarettes are individually fed by said feeding device thereby contacting the cigarettes individually; and means cooperating with the feelers to set the ejecting apparatus in operation when a cigarette detected by one or more of the feelers contains an under or over supply of tobacco.

80 6. An apparatus for detecting and setting an ejecting apparatus in operation for an incorrectly filled cigarette or the like, comprising an individual feeding device for the cigarettes; a plurality of spring-pressed feelers pivotally arranged side by side lengthwise and along which the cigarettes are individually fed by said feeding device thereby contacting the cigarettes individually; and means cooperating with the feelers to set the ejecting apparatus in operation when a cigarette detected by one or more of the feelers contains an under or over supply of tobacco.

85 In testimony whereof I have affixed my signature.

ARTHUR RITSCHER.
